UNITED STATES PATENT OFFICE.

GEORGE CUGLEY, OF SPRINGFIELD, OHIO, ASSIGNOR TO THE BUCKEYE INCUBATOR COMPANY, OF SPRINGFIELD, OHIO, A CORPORATION OF OHIO.

BROODER.

Application filed June 25, 1923. Serial No. 647,630.

To all whom it may concern:

Be it known that I, GEORGE CUGLEY, a citizen of the United States, residing at Springfield, in the county of Clark and 5 State of Ohio, have invented certain new and useful Improvements in Brooders, of which the following is a specification, reference being had therein to the accompanying drawings.

10 My invention relates to brooders and more particularly to a brooder for young chicks that employs a cone shaped metal canopy supported over a floor with its lower edges a sufficient distance above the floor to 15 give the chicks easy access to the space or chamber under the canopy.

It has been common to heat such space or chamber with a centrally located oil burner; but such burners do not give a sufficient 20 temperature at the outer or more exposed portion of the chamber and the chicks are tempted to crowd in toward the center of the chamber.

The object of my invention is to provide 25 means to convey or transmit the heat of the burner to the outer or more exposed portions of the chamber and this I accomplish by employing a heat conveyor plate disposed over the burner to absorb and convey 30 the heat therefrom to its outer edges which are secured to and in contact with the canopy, so that the heat is transmitted to and further carried thereby to its outer extremities; and I have obtained the best results 35 with a heat conveyor plate of a diameter equal to or greater than one-half the greatest diameter of the canopy. In practice I have found that by the use of this conveyor plate the temperature at the outer or more 40 exposed portion of the space or chamber is increased fifteen per cent.

Suitable openings through the canopy and heat conveyor plate are provided for the 45 proper ventilation and the escape of foul gases.

While I have shown and described a canopy conical in shape any suitable form of canopy may be employed.

With these and other objects in view my 50 invention consists of the constructions and combinations hereinafter more fully described and set forth in the claim.

In the accompanying drawings which 55 form a part of this specification Fig. 1 is a side elevation of a brooder with the canopy

in section, the same as shown embodying my invention, Fig. 2 is a plan view of the brooder without the canopy, Fig. 3 is an enlarged sectional view of the reservoir and container, Fig. 4 is an enlarged sectional view of the burner, Fig. 5 is a side elevation partly in section of the canopy, Fig. 6 is a plan view of the canopy and heat conveyor plate, inverted, Fig. 7 is a perspective view of a ventilator cap for the canopy. 60 65

Like numerals represent the same parts in the several views.

In the drawings 1 represents a metal canopy preferably cone shaped as shown supported by legs 2 a suitable distance from the floor to admit the chicks to the space or chamber covered by the canopy. A heat conveyor plate 3, slightly conical in form to afford stability, is secured to the canopy by clips 4. A ventilator cap 5 having the opening 6 is provided which together with the opening 7 in the outer edges of the heat conveyor plate affords means for the escape of foul gases from the brooder chamber. It will be seen that the heater conveyor plate 80 is so secured to the canopy that the outer edges of the plate are in contact with the canopy so that the heat conveyed by the plate will be transmitted to the canopy and carried thereby to its outer extremity. 85

An oil reservoir 8 supported by legs 9 is provided with a bracket 10 supporting as shown an oil container 11 having an opening 12 through a projecting neck 13 which opening is normally closed by a spring 90 pressed valve 14. It will be seen that the container may be lifted from its seat by a bail 15 and inverted and when inverted as shown in Fig. 3, the valve stem 16 contacts the bottom of the reservoir and lifts the valve to open position, so that when the oil in the reservoir falls below the lower end of the opening 12 air will be admitted to the container and the oil will flow from the container to maintain a constant level in 95 the reservoir.

Any suitable type of wick burner may be used but I will now describe a burner that I have successfully employed together with the means for attaching it to the oil supply. 105 The supply pipe 17 with a supporting leg 17^a has an opening 18 which connects with a like opening in a casting 19 soldered to the pipe. An end 20 of this casting fits into a recess of a casting 21 soldered to the lower 110

cylinder of the burner. This casting is held rigidly in place on the pipe by a clamp 22 which extends around the castings 19 and 21 and a screw 23 forces the end 20 into the recess in the casting 21 forming a leak proof joint. An opening through the casting 19 permits the oil to flow from the openings in the pipe and casting 19 to an annular chamber 24 in the lower burner cylinders. 10 The lower burner cylinders consist of an outer cylinder 25 and an inner cylinder 26 made from a single sheet of metal U-shaped in form with its closed end at the bottom forming said chamber. A cylindrical wick 27 carried by a perforated sleeve 28 fits in the chamber 24 and is raised and lowered by a sprocket wheel 29, the teeth of the wheel engaging the perforations of the sleeve. Said sleeve extends about half the length of 15 20 the wick and is carried around the lower end of the wick and crimped in such a manner as to hold it securely when the wick is raised and lowered.

A core 30 is secured to the inner cylinder 26 so that a proper amount of air is introduced to the flame for combustion. Within the dome 31 the upper perforated cylinders 32 and 33 are disposed forming an annular chamber in line with the cylindrical wick 30 and the heat passes through said cylinder and the opening 34 in the drum cover directly against the heat conveyor plate 3 by which it is absorbed and carried to the outer

or more exposed portion of the brooder chamber as hereinbefore pointed out. 35

The supporting legs of the reservoir and supply pipe are of such length that when seated on a level floor the oil will flow from its level in the reservoir to a corresponding and proper level for consumption in the annular chamber 24, said levels being marked X in the drawings; and in the event of a variation of the level of the oil in said chamber caused by an uneven sagging or buckling floor the wick will continue to 40 45 supply oil for the flame.

An opening 35 in the canopy gives access to the burner and a closure 36 is provided for said opening. The reservoir and burner are securely attached to each other by the 50 supply pipe so that they may be moved together.

Having thus described my invention I claim:

The combination with a canopy for a 55 brooder, of a heat conveyor plate in said canopy with peripheral contact therewith, whereby heat conveyed by the plate will be transmitted to the canopy and carried thereby to its outer extremities, and exit ports 60 in said plate and canopy for the escape of foul gases.

In testimony whereof I have hereunto affixed my signature.

GEORGE CUGLEY.
